UNITED STATES PATENT OFFICE.

HENRY ZIMMERN, OF NEW YORK, N. Y.

DESIGN FOR A WATCHMAKER'S TOOL.

SPECIFICATION forming part of Design No. 27,713, dated October 12, 1897.

Application filed April 23, 1897. Serial No. 633,539. Term of patent 7 years.

To all whom it may concern:

Be it known that I, HENRY ZIMMERN, a citizen of the United States, residing at New York city, county and State of New York, 5 have invented and produced a new and original Design for a Watchmaker's Tool, of which the following is a specification, reference being had to the accompanying drawings, showing had to the accompanying drawings, showing a part thereof.

Figure 1 is a side elevation of the tool, showing my design. Fig. 2 is a section of the same through line $x x$ of Fig. 1.

The leading feature of my design is a disk, in the drawing marked A, having a series of 15 radially-arranged sleeve-keys C, which project in uniform length from the edge of the

disk A at regular intervals. The sleeve-keys are of different diameters, and their outer ends D are provided with a series of points, as shown in the accompanying drawings. 20

The section Fig. 2 shows that the disk A is of a considerable thickness to admit the setting of the base of the key in the edge of the disk. Both sides of this disk present the same design. 25

What I claim is—

The design for a watchmaker's tool herein shown and described.

HENRY ZIMMERN.
